BOILER CONSTRUCTION

John Phillips Badenhausen, Philadelphia, Pa.,
assignor of one-half to Day and Zimmermann,
Incorporated, Philadelphia, Pa., a corporation
of Maryland

Application September 5, 1935, Serial No. 39,254

5 Claims. (Cl. 122—478)

My invention relates to boilers and more particularly to boilers of large capacity using pulverized coal as a fuel therefor.

Up to the present time, in the designing of boilers with water cooled walls and for the combustion of pulverized coal, liquid fuel, and the like, it has been rather common to try to utilize the steam generating designs of ordinary boiler construction and to add thereto provisions for cooling the walls of the combustion chamber and for discharging the steam and hot water from the cooling walls directly into the circulatory system of the steam generating section; the result of this has been to make the completed structure increasingly higher, as the capacity of the boiler was increased, thereby making the boilers occupy too much valuable space. There has not been very much of an endeavor manifested to completely re-design a steam generator for use with such fuels without reference to standard boilers, designed to burn ordinary coal.

The object of the present invention is to simplify the design of boilers using finely divided fuels, by providing the steam-generating section thereof with merely one large steam and water drum, with two relatively small headers and with as few water tubes as possible connecting said drum and headers.

A further object of this invention is to provide a construction whereby the gases of combustion, reaching the superheater, are of relatively higher temperature than they are in boilers, as heretofore constructed, thereby enabling me to reduce the heating surfaces of the superheater and with that the cost of the same.

A further object of this invention is to provide a construction which will make the over-all height and also the depth of the boiler considerably less than the corresponding dimensions of a boiler of equal capacity as constructed up to the present time.

A further object of this invention is to make possible the placement of an air heater or economizer, or both, within the space heretofore occupied by the large mud drum and the large bank of downcomer tubes connecting the mud drum with the steam-and-water drum with which boilers of this type have been heretofore provided.

A further object of this invention is to utilize an economizer as an active part of the main heating surfaces of the boiler thereby substituting the very compact arrangement of economizer tubes with its great heat absorptive properties for the relatively widely spaced aggregations of tubes heretofore employed, thereby utilizing

the greater heat-absorption properties of the economizer, over that of the ordinary boiler tubes in the steam-generating section.

The heating surfaces of the ordinary boiler or steam generator is divided into upcomers and downcomers. Since water in the heating surfaces, absorbing heat, will tend to rise naturally and since the heating of the upcomer tubes increases the upward rise of the water therein, it follows that the heating of the downcomers tends to retard the downward flow in the downcomers. This, therefore, results in an unequal circulation of the water, which will be faster in the upcomers than in the downcomers and this may result in the failure of the water to move in certain of the tubes with a consequent overheating and sagging of some of the tubes. The natural flow of the water in the tubes should always be upward and the downcomers should be subjected, if possible, to a minimum exposure to the gas flow, or to a minimum heating surface in the boiler gases. The greater the heat of the water in the boiler the faster will be the velocity of the circulation in the upcomers. All of this tends to disturb the proper circulation of water within the steam generating section.

A further object of the present invention is, therefore, to provide a construction for the free, unimpeded circulation of the water in the steam-generating section of the boiler and in the water walls, from the bottom of the structure toward the steam-and-water drum, by shielding the downcomers as much as possible from the radiant heat of the combustion chamber and by supplying the coolest water in the boiler to the steam generating section and to the wall cooling at points near the bottom of the boiler structure, whence it freely circulates upwardly throughout the tubes.

Other objects of my invention will appear in the specification and claims below.

In the drawings forming a part of this specification and in which like reference characters are employed throughout the view to designate the same parts,

Fig. 1 is a vertical longitudinal section of the essentials of a steam-generator or boiler embodying my invention.

Fig. 2 is a similar transverse sectional view of the upper banks of tubes of the steam-generator.

Fig. 3 is a similar view of the tubes leading from the side walls into the ends of the steam-and-water drum.

Fig. 4 is a diagrammatic layout of the development of the surfaces of the steam-and-water

drum, the intermediate header, the lower header and the upper header of the cooling section of a side wall of a boiler, to clearly indicate the connections of the banks of tubes thereto.

5 Referring now particularly to Fig. 1, the boiler comprises a steam-and-water drum A, a relatively small intermediate header B and a relatively small lower header C. The intermediate header B is connected to the steam-and-water header 10 drum A by two banks D and E of tubes and the steam-and-water drum A is connected with the lower header C by a bank F of downcomer tubes, which is entirely shielded from the radiant heat of the combustion chamber by the baffle G and the rear wall H of the furnace.

15 The intermediate header B and the lower header C are connected by a relatively small double bank I of steam-generator tubes.

20 It will thus be seen that the circulation of the water in the steam-generating section of the boiler is continually upwardly in the banks D, E and in the bank I of tubes, the downcomer bank F being completely shielded from the radiant heat of the combustion chamber, and located in that 25 portion of the boiler where the gases of combustion are comparatively cool.

25 Only one of the side walls J is shown in the drawings, it being understood that both side walls of the boiler are substantially alike. Each 30 is water-cooled by a bank K of tubes extending vertically and close to the wall, the opposite ends of the bank being connected respectively to the upper side-wall header L and to the lower side-wall header M. The lower header M is connected 35 to the lower boiler header C by a set of tubes m outside of the side wall J, by which they are shielded from the radiant heat of the combustion chamber. Each of the upper side wall headers L is connected by a bank of tubes N with the 40 steam-and-water drum A at the end of the drum beyond and beside the banks D and E of the generator section of the boiler, and on the inner surface of the side wall which is water cooled thereby.

45 The rear wall H and the baffle G are water cooled by two banks O and P of risers extending upwardly adjacent thereto and extending from the lower header C directly to the steam-and-water drum A, the banks passing through the upper portion of the baffle G. The bank O lies 50 behind but on the outer side of the wall H, but passes through it at the top thereof and lies on the inner side of the baffle G, and the bank P lies on the inner side of the wall H and on the inner 55 side of the baffle G. Both said banks are thus exposed to the radiant heat of the combustion chamber.

60 The economizer Q which may be of standard construction, is preferably within the boiler beneath the steam-and-water drum A. It occupies the space usually occupied by the large bank of downcomer tubes heretofore employed in a water circulating type of steam generator. Gases of 65 combustion, after passing from the combustion chamber and over the banks of steam-generating tubes D, E are conducted into the upper end of the economizer Q which presents a much greater capacity for absorbing the heat from the 70 gases than the loose congregation of steam generating tubes heretofore utilized in boiler construction. The lower end of the economizer 75 communicates directly with the lower end of the air heater R (of usual construction) in which the air forced into the upper end of the heater R is

heated and conveyed therefrom by the air conduit S to the pulverized fuel burners T.

Feed water is introduced into the lower end of the economizer by the pipe U and the heated steaming water therefrom is delivered by a bank V of tubes communicating with the underside of the steam-and-water drum A, whence it passes to the bank F of downcomers communicating respectively with the lower header C, the lowest point in the generating section, the lowest point 10 of the banks O and P of risers, and to the lowest headers M of the side wall banks K through tubes m.

15 It is here to be observed that this arrangement of the banks of steam-generator and wall cooling tubes is of particular advantage in enabling me to locate and install the superheater W in substantially the hottest part of the boiler immediately over the staggered small bank I of generator tubes. This enables me to reduce to 20 a minimum, the heating surface of the tubes of the superheater, and to thus substantially reduce the cost of construction. The superheater W may be connected to the steam space of the 25 steam-and-water drum A by a pipe X, and the superheated steam may be delivered from the superheater by the pipe Y.

30 Referring now to the development of the surfaces of the steam-and-water drum A, the headers B, C and the side wall upper header L as shown in Fig. 4, it will be seen that by staggering the upper ends of the banks D and E of the steam-generating section, where they are connected to the steam-and-water drum A greater 35 space may be provided between the circumferential rows of holes in the steam-and-water drums than is provided in ordinary steam-generator construction, thereby substantially increasing the ligature strength of the drum to 40 adapt it to the high pressures now availed of in boilers of this type, and without increasing the thickness of the wall of said drum.

45 The tubes of the various banks of tubes are designated in Fig. 4 by lower case letters corresponding to the capital letters heretofore employed in referring to the banks as a whole. The 50 points of attachment of the tubes to the steam-and-water drum A, to the intermediate header B, the lower header C and to the top side wall header M are clearly indicated. The tubes d¹ to d⁴, of bank D are disposed in a row extending circumferentially of the drum A, connect, and are connected to the intermediate header B at d¹, d², d³, d⁴ respectively. The tubes e¹, e², e³, e⁴, of the bank E are connected to the intermediate header B in a staggered relationship at e¹, e², e³, e⁴ respectively. The ligature strength of the small header B may be maintained by increasing the thickness of its wall.

55 The banks O and P of riser tubes o and p of the steam generator extend upwardly from the lower header C to the steam-and-water drum A are indicated as the pipes o and p in Fig. 4. They 60 are preferably in a staggered relationship with respect to the drum A and with respect to the header C. The position of the bank F of shielded downcomer pipes f is indicated clearly in the developments of the surface of the drum A and lower header C. On the drum A (Fig. 4) is also indicated the positions of the pipes v¹, v², leading 65 from the economizer Q. In Fig. 4 is also indicated the position of the pipes i¹ and i² of the bank I, extending from the header B to the header C. The position of the riser tubes o alternate 70 with the downcomer tubes F back of the wall H 75

and are preferably staggered in their connections with the header C and drum A.

At the ends of the drum A is a row of tubes n^1 to n^{14} comprising the bank N and indicated on 5 the development of the drum A and of the header L, and the ligature strength of the drum A is thus retained.

It will be readily seen that the top wall Z of the combustion chamber is water-cooled by the upper 10 tubes d^1 of the bank D and by the upper tubes n^1 of the bank N; that the side walls are cooled by the banks K and the banks N and that the rear wall and baffle are cooled by the riser tubes o, p, and by the downcomer pipes f and that the cooler 15 water of the system is conducted from the steam-and-water drum A through the bank F to the lower header C whence it is distributed through the pipes or tubes m^1 , m^2 , m^3 , m^4 to the lower side wall headers M and to the bank J of the steam-generator section to the riser tubes o and p.

Thus in the circulatory system of the generator section and of the wall cooling section, the direction of the flow of water in all of the tubes except in the single downcomer bank F is upwardly. The large bank of the downcomer tubes, found in former constructions has been eliminated; the large mud drum of the old constructions has also been eliminated; and space within the boiler walls is provided for the placement of 30 the economizer, which most efficiently abstracts the heat from the gases leaving the boiler and transfers it to the incoming feed water. The water, delivered from the economizer to the steam-and-water drum is at a high steaming temperature because of the reduction in the area of the heating surface of the tubes of the steam generating section. I have shown the front or fore wall Z^1 of the furnace chamber as being made of refractory material, but it is to be understood that this wall may be water-cooled in like manner when so desired.

Having thus described my invention, what I claim and desire to protect by Letters Patent of the United States, is:

45 1. In a boiler for the combustion of finely divided fuel, the combination with a combustion chamber provided with a rear wall, of a relatively large steam-and-water drum at the top of the boiler in the rear portion thereof, a relatively 50 small intermediate header at the front of the boiler and at a lower level than said drum, a relatively small lower header at the bottom of the said boiler at the rear portion thereof, a relatively small bank of riser tubes exposed to the 55 radiant heat in said combustion chamber and directly connecting said lower header with said intermediate header, a bank of riser tubes exposed to the radiant heat of said combustion chamber directly connecting said front header 60 with said steam-and-water drum, a plurality of banks of riser tubes extending upwardly along said rear wall and directly connecting said lower header with said drum, one of said banks of tubes having the lower portion shielded from the radiant heat of the combustion chamber by said rear 65 wall and another of said banks being shielded from the radiant heat at the upper portions thereof, and a relatively small bank of downcomer tubes directly connecting said steam-and- 70 water drum with said lower header and shielded from the radiant heat of the combustion chamber.

75 2. In a boiler for the combustion of finely divided fuel, the combination with the combustion chamber of a steam generating section and a wall

cooling section, said generating section comprising a large steam-and-water drum at the top of said boiler in the rear portion thereof, a relatively small intermediate header at the front of said boiler and at a lower level than said drum, a relatively small lower header at the bottom of said boiler at the rear portion thereof, a relatively small bank of riser tubes connecting said lower header with said intermediate header, a bank of riser tubes connecting said intermediate header with said drum, and a relatively small bank of downcomer tubes connecting the lower side of said drum with said lower header and shielded from the direct radiant heat of said combustion chamber, said wall cooling section including a bank of riser tubes substantially covering the rear wall of said combustion chamber, said riser tubes being shielded for portions of their length and being connected at their upper ends directly to said steam-and-water drum and connected at their lower ends directly to said lower header, said wall cooling section also including banks of riser tubes covering the side walls and having their upper ends connected to said steam-and-water drum and having their lower ends connected to said lower header, whereby the relatively cooler water delivered from said steam-and-water drum to said lower header, flows upwardly throughout the steam generating and throughout the wall cooling sections 30 from the lowest part of said boiler back to said steam-and-water drum.

3. In a boiler for the combustion of finely divided fuel and the like, the combination with a combustion chamber of a steam generating section, a wall cooling section, and an economizer section, said generating section including a relatively large steam-and-water drum in the top of the boiler at the rear thereof, a relatively small intermediate header at the front of said boiler 40 at a lower level than the said drum, a relatively small lower mud header at the bottom of the said boiler at the rear portion thereof, a relatively small bank of riser tubes connecting said lower header with said intermediate header and having portions extending from the rear to the front in the upper portion of the combustion chamber, a bank of riser tubes connecting said intermediate header with said steam-and-water drum and having portions shielded from the radiant heat 50 of said combustion chamber, said wall cooling section including banks of riser tubes substantially covering the side walls of said combustion chamber, said riser tubes being connected at their upper ends to said steam-and-water drum and connected at their lower ends with said lower header, said wall cooling section also including banks of riser tubes extending upwardly along the rear wall of said combustion chamber, said riser tubes being connected at their upper 55 ends directly to said steam-and-water drum, and connected at their lower ends directly to said lower header and having portions shielded from the radiant heat of said combustion chamber, said economizer section being provided beneath said steam-and-water drum, and having riser tubes connected thereto, and a bank of downcomer tubes connecting said steam-and-water drum and said lower header and shielded from the radiant heat of said combustion chamber.

4. In a boiler for the combustion of finely divided fuel and the like, the combination with a combustion chamber of a steam generating section, and a wall cooling section, said generating

section including a relatively large steam-and-water drum in the top of the boiler at the rear thereof, a relatively small intermediate header at the front of said boiler and below the level 5 of the said drum, a relatively small lower mud header at the bottom of the said boiler at the rear portion thereof, a relatively small bank of riser tubes connecting said lower header with said intermediate header and extending from the 10 rear to the front in the upper portion of the combustion chamber, a bank of riser tubes connecting said intermediate header with said steam-and-water drum, said wall cooling section including banks of riser tubes substantially covering the side walls of said combustion chamber, said riser tubes being connected at their upper ends to the steam-and-water drum and connected at their lower ends with said lower header, said wall cooling section also including banks of 15 riser tubes extending upwardly along the rear wall of said combustion chamber, said riser tubes being connected at their upper ends directly to said steam-and-water drum, and connected at their lower ends directly to said lower header, and having portions shielded from the radiant heat of said combustion chamber, and a bank of 20 downcomer tubes connecting said steam-and-water drum and said lower header and shielded from the radiant heat of said combustion chamber, said riser tubes being connected at their upper ends directly to said steam-and-water drum, and connected at their lower ends directly to said lower header, said wall cooling section 25 also including banks of riser tubes extending upwardly along the rear wall of said combustion chamber, said riser tubes being connected at their upper ends directly to said steam-and-water drum, and connected at their lower ends directly to said lower header and having portions shielded from the radiant heat of said combustion chamber, said economizer section being provided beneath said steam-and-water drum and having riser tubes connected thereto, said superheater being relatively small and being positioned within said combustion chamber above the bank of riser tubes connecting the said headers and below the bank of riser tubes connecting the intermediate header with the steam-and-water drum. 30

5. In a boiler for the combustion of finely divided fuel and the like, the combination with a combustion chamber of a steam generating section, a wall cooling section, an economizer section and a superheater, said generating section including a relatively large steam-and-water drum in the top of the boiler at the rear thereof, 35

a relatively small intermediate header at the front of said boiler at a lower level than said drum, a relatively small lower mud header at the bottom of the said boiler at the rear portion thereof, a relatively small bank of staggered riser tubes connecting said lower header with said intermediate header, a bank of riser tubes connecting said intermediate header with said steam-and-water drum having portions shielded from the radiant heat of said combustion chamber, and a bank of downcomer tubes connecting the lower side of said steam-and-water drum with said lower header and shielded from the radiant heat of said combustion chamber, said wall cooling section including banks of riser tubes 10 substantially covering the side walls of said combustion chamber, said riser tubes being connected at their upper ends to said steam-and-water drum and connected at their lower ends with said lower header, said wall cooling section 15 also including banks of riser tubes extending upwardly along the rear wall of said combustion chamber, said riser tubes being connected at their upper ends directly to said steam-and-water drum, and connected at their lower ends directly to said lower header and having portions shielded from the radiant heat of said combustion chamber, said economizer section being provided beneath said steam-and-water drum and having riser tubes connected thereto, said superheater being relatively small and being positioned within said combustion chamber above the bank of riser tubes connecting the said headers and below the bank of riser tubes connecting the intermediate header with the steam-and-water drum. 20
